UNITED STATES PATENT OFFICE

HARRY W. KULP AND MARTIN C. DELLINGER, OF LANCASTER, PENNSYLVANIA

VALVE-SPRING LIFTER

Application filed August 3, 1931. Serial No. 554,925.

This invention relates to valve-spring lifters or compressors for use in compressing or lifting the lower end of the valve stems as arranged about the valve stems of the 5 poppet valve type internal combustion engines, to permit the retaining or locking elements or key to be easily removed or to drop out or to be inserted in removing or replacing the valves and their stems, incident 10 to the grinding of the valves or their removal or adjustment for any reason and the present invention relates to certain improvements in that type of valve-spring lifters forming the subject matter of our 15 pending application for United States patent, Ser. No. 457,027, filed May 29, 1930, and patented June 14, 1932, No. 1,862,793.

In use of the lifters embodying the invention set forth in said above identified 20 pending application, it has been found that in a number of instances the mechanic adjusts the position of the adjustable post to what he thinks is about the proper position and then applies the lifter to the lower end 25 of one of the springs with the foot of the post on the top of the corresponding valve and moves the hand lever to cause upward movement of the lower jaws to lift the spring. If the mechanic has properly 30 guessed the position of the post this works all right. However, if he has misjudged the position, either the spring will not be raised sufficiently to allow the horse shoe type retainers to drop out of position, or 35 the key or lock, where that is employed, to be removed, or else, if he has misjudged the position in the other direction the spring D will be compressed or raised to its extreme 40 point before the operating lever and link have passed over dead center and, since it is necessary for them to pass over dead center in order to lock, the mechanic is prone to force them over dead center anyway and in so doing springs or bends and permanently deforms the frame of the lifter. If 45 an effort be made by the mechanic to adjust the position of the post so as to get the proper lift of the spring while the lifter is operatively applied and has compressed the 50 spring to any extent, as soon as he frees the

post for endwise movement in its sleeve or collar the sleeve, under the influence of the spring pressure will move suddenly with relation to the post, making it very difficult for the mechanic to judge the former relative position between the post and sleeve and hence robbing him of the advantage of his previously formed estimate as to the adjustment necessary. In view of the foregoing, if the original rough estimate as to proper position was anywhere near the correct adjustment those mechanics using this tool usually are content to let it go at that, struggling with the keepers or key to get them free if the spring has not been raised 60 to the most efficient point, or spring the frame of the lifter in case the adjustment is such as to raise the lower jaws of the lifter 65 higher than is necessary. It is to be borne in mind that when the position of the post has once been set for a particular engine the lifting or compressing operation for all 70 of the springs of the valve of said engine is thereafter performed on that particular engine with the post in such adjustment, with the consequence, if the adjustment be slightly wrong one way or the other, that either the springs are not lifted high enough 75 to enable the mechanic to most efficiently perform the operation, or else the frame of 80 the lifter is sprung, and this is repeated a number of times on each engine with consequent total of either substantial loss of efficiency or injury and excessive wear of the 85 lifter itself.

The present invention has particularly in view to overcome the above mentioned defects and to provide two separate means either operable independently or in combination with each other for causing the lifting and lowering of the lower jaws incident to the compression and release of the lower end of the valve-spring, one of said means serving as a control adjusting means for the post for altering its vertical position in its cooperating sleeve while the tool is holding a valve-spring compressed or raised, whereby the post may be adjusted to exactly the right position so as to lift the valve-spring 90 to the correct height to permit the most 95 100

efficient removal of the horse shoe keepers or cross pin, while avoiding any such jamming between the compressed spring, post and operating levers, such as would result 5 in springing the lifter frame, making it practical to adjust the post to exactly the right position on lifting the first valve-spring of the engine, after which the post will be left in such position of adjustment 10 during the use of the tool on all other valve-springs of that particular engine.

In the accompanying drawing:

Figure 1 represents a perspective view of the valve lifter embodying our present invention as operatively applied in servicing 15 an internal combustion engine;

Figure 2, a front elevation of the tool showing the position of the parts in solid lines after the hand lever has been moved 20 to compressing or lifting position with the post 18 in an approximate position of adjustment, and illustrating in dotted lines the position of the parts after the hand wheel 21 has been turned to adjust the vertical 25 position of the post 18 through the sleeve 10 to the proper position, so as to lift the lower end of the valve-spring to the most efficient point without springing or damaging the frame of the lifter;

Figure 3, a vertical sectional view on the line 3—3 of Figure 4, looking in the direction of the arrows; and

Figure 4, a vertical sectional view on the line 4—4 of Figure 3, looking in the direction of the arrows.

Referring now in detail to the drawing, A designates a conventional internal combustion engine having poppet valves such as B, with valve-stems C about which are 40 respectively arranged valve springs such as D, having their respective lower ends bearing on a cup or washer E, said cup or washer E being normally prevented from slipping down off the end of the valve-stem C by locking elements or horse shoes, not shown, adapted to engage the upper face of the annular shoulder or enlargement F at the lower end of the stem C and normally forced radially inwardly toward each other 45 by locking elements or horse shoes, not shown, adapted to engage the upper face of the intervening tapering portion of the valve-stem C by the cooperating lower face of the cup or washer E, all in accordance with usual well known practice, or any suitable means functioning as locking elements, such as a cotter-pin or cross-pin long well known in this art for this particular 50 function, may be employed.

The valve-spring lifter comprises a foot 60 1 adapted to rest on the upper face of the valve B, a pair of jaws 2 adapted to straddle the valve-stem C and engage the lower face of the cup or washer E, a C-shape type frame 3, two parallel movement arms 4 and 5 pivotally mounted adjacent each other at 65 one end between the upper portions of the

plates of the frame 3 on pivot pins 6 and 7 respectively and having their inner ends pivotally connected between the side portions of the sleeve 10 by means of the pivot pins 8 and 9 respectively. An operating handle 11 pivotally mounted between the extreme upper end portions of the plates of the frame 3 by means of a pivot pin 12 and having a cam 13 adapted to engage the upper edge face of arm 4 to limit the pivotal movement of the handle 11 towards arm 4 is operatively connected to one of the parallel movement levers, for instance lever 5 as illustrated in the drawing, by means of pivot pins 15 and 16 in such relation that when the face of the cam 13 is flat against the upper edge of lever 4 the longitudinal central line of the link 14 will extend below and to the rear of the pivot pin 12, pivotally mounting the lever 11 in the frame, thus locking the lever 11 in the contracted lifted condition of the jaws of the lever when applied in the lifting operation of the valve-spring. The foot 1 is carried on the lower end of a vertical post 18 vertically adjustable through the sleeve 10 to adjust the degree of lifting of the lower end of, or compression of, the valve-spring B.

All of the above mentioned elements form the subject matter of our invention as disclosed in said pending application Ser. No. 457,027, and are very fully described therein in detail, and therefore it is not believed that further detailed description is necessary or desirable herein.

In the present invention we have formed the vertical edge of the post 18 as a rack or with a plurality of teeth 19 and have rotatably mounted a small pinion 20 between the opposed faces of the sleeve 10 and in such position as to mesh with the teeth 19 of the post 18 so that rotation of said pinion 20 will cause corresponding endwise movement in a vertical direction of the post 18. Said pinion 20 may be integral with the shaft 21a of a hand wheel 21, said shaft extending through and being journaled in a corresponding circular opening or bore in one side of the sleeve 10 and having a reduced extreme end portion extending through a co-axial bore in the other side of said sleeve 10 and receiving on the portion thereof extending therethrough a washer 21' and having its extreme end spread or upset beyond said washer so as to permanently mount and retain the parts in such assembled relation.

A preferably sheet metal approximately U-shape yieldingly pressed stop straddling the lower rear portion of the sleeve 10 is pivotally mounted thereon by means of a pivot pin 23 extending through the upper ends of the arms of said stop and the intervening portion of said sleeve and is provided with a stop flange or lip 24 normally

fitting between two of the adjacent teeth 19 and lying in engagement with the lower edge face of the sleeve 10 so as to unyieldingly lock the post 18 in adjusted position 5 in the sleeve 10 against the influence of the upward thrust transmitted to said post 18 through the foot 1 by the compressed spring D. The lower rear corners of the sleeve 10 are rounded off to permit the rearward 10 swinging of the keeper 22 with its stop flange or lip 24 out of operative position, in this respect being substantially the same as illustrated and described in said application Ser. No. 457,027, and said stop is formed 15 with a retracting finger piece 25 by which it may be pressed rearward out of operative position and retained inoperative by the operator's finger at will.

Suitable spring means or resilient means 20 for normally urging the stop 22 into and yieldingly retaining it in operative position engaging between the teeth 18 of the post 19 will be provided, and said means will preferably be a wire spring coiled about the 25 pivot pin 23 with one end hooked over or anchored to the sleeve 10 and with a long arm depending downward from pivot 23 under compression and having an end portion bearing against the upper part of the rear 30 face of the finger grip 25 so as to force the lower end of the stop or lock or latch 22 forward about its pivot 23.

From the foregoing it is obvious that the post 18 may be raised or lowered with relation 35 to the sleeve 10 by rotating the pinion 20 in the proper direction; that when the post 18 is being forced downward through the sleeve by the pinion 20, the inclined faces of the teeth 19 will successively engage 40 the forward upper edge of the stop flange or lip 24 of the stop 22 and will cause the stop 22 to rock rearwardly about its pivot 23 to such extent as to successively release the downwardly moving teeth 19; and that 45 under the influence of the compressed spring D the upper face of the tooth 19 below and next adjacent to the stop lip or flange 24 will engage the same and force it upward against the lower edge of the sleeve 10 with 50 a tendency to rotate it forwardly and so jam the flange 24 between the lower edge of the sleeve 10 and the upper face of said tooth 19, thus locking the post 18 against upward movement with respect to the sleeve 10 so 55 long as the lock 22 is not held to the rear out of operative position; and that by holding the lock 22 rearward out of operative engagement with the teeth 19 and gripping the hand wheel 21, the post 18 may move 60 upward with respect to the sleeve 10 as slowly or rapidly as the mechanic may desire and the control exerted by the strength of his grip will permit.

In operation, assuming the post 18 to have 65 been adjusted to an approximate position

as indicated in full lines in Fig. 2 and the hand lever 11 having been moved to compressing locked position, the post 18 may be adjusted vertically downward through the sleeve 10 by turning the hand wheel 21 to cause relative movement between the post 18 and the other parts of the lifter as indicated in dotted lines in Fig. 2, which dotted line position is to be taken as the correct relative adjustment of the parts for servicing a particular engine. Thereafter the parts will be left in this adjustment until the compression or lifting of all of the valve-springs of that particular engine have been completed.

However, some mechanics prefer a hand wheel operated type of lifter, while others prefer a lever operated lifter, and sometimes, regardless of the preferences of the particular mechanic, the working space and conditions are such that only a lever operated lifter can be operated, and in other circumstances the space and conditions are such that a lever operated lifter cannot be easily operated. The present invention is of such construction as to permit selectivity of the mode of operation to meet all such preferences and all such operating conditions, as the post 18 may be adjusted to the proper height in the sleeve 10 and thereafter the operation of the lifter may be entirely by means of the lifter 11 or the lifter 11 may be moved to the locked or contracted position as shown in Figs. 1 and 2, and the post 18 may be forced downward through the sleeve 10 to compress the spring to the most efficient point and thereafter the latch or lock 22 may be moved rearward to inoperative position and the post 18 allowed to move upward under the thrust of the spring D and under the control of the mechanic's hand grip on wheel 21 in either the removal or replacement of the spring D.

Preferably the upper portion of the rear edge face of the post 18 is left intact solid with the teeth and the post 18 is inserted in the sleeve 10 before the pinion 20 is mounted therein in engagement with the teeth 19, whereby after said pinion 20 is mounted in said sleeve 10 in mesh with the teeth 19, said post 18 will be permanently locked in the sleeve 10 against separation therefrom and possible loss, since obviously the teeth of the gear 20 in engaging in the last upper notch of the rack or between the teeth 19 and striking against the portion 18a cannot turn any further and being in engagement with the next lower tooth and/or with the upwardly inclined lower face of the portion 18a, will definitely prevent further downward movement of the post 18 through the sleeve 10, whereas the foot 1 permanently rigidly mounted on the bottom of the post 18 obviously prevents separation in an up-

ward direction of the post 18 from the sleeve 10.

Obviously any suitable rack or tooth design and construction may be substituted for the rack or teeth 19; any suitable gear or other operating construction functioning to raise or lower the post 18 by constant engagement with said rack may be substituted for the pinion 20 with its shaft 21a, its hand wheel 21 and retaining washer 21'; and any suitable means automatically yielding to permit the downward movement of the post 18 through the sleeve 10 and normally adapted to prevent upward movement of the post 18 through the sleeve 10 may be substituted for the latch or stop 22 with its associated parts.

Having thus described our invention, what we claim as new and desire to secure by Letters Patent is:

1. A valve-spring lifting tool comprising a frame, a pair of jaws mounted on said frame, a sleeve, a pair of parallel movement levers pivotally connected at their respective end portions to said frame and to said sleeve respectively, a handle pivotally mounted in the upper portion of said frame adjacent to one of said arms, said handle being provided with a cam having a long straight lower edge face substantially parallel with the opposed edge face of said adjacent arm when in engagement therewith, a thrust link, and pivot pins respectively pivotally connecting the respective end portions of said link to said cam and the distant arm, said lower face of said cam engaging the opposed upper face of the adjacent arm in the closed position of the tool, and in such position the line of thrust of said thrust link extending below and to the rear of the pivotal point of mounting of said handle in said frame, in combination with a post slidably mounted in said sleeve and formed with a vertically extending series of rack teeth, a pinion journaled in said sleeve and meshing with the teeth of said post, means for at will rotating said pinion, a catch straddling the lower rear portion of said sleeve and pivotally mounted on said sleeve for swinging movement toward and from said post, said catch normally operatively engaging the lower face of said sleeve and the opposed upper face of one of the teeth of said series to lock said post against movement in said sleeve away from said jaws under the thrust of the valve-spring being operated upon, and yielding means for normally holding said catch in operative position, said yielding means being adapted to automatically yield under the downward and rearward thrust of the next adjacent upper tooth to permit said post to be moved downward through said sleeve by the rotation of said pinion in the proper direction.

2. A valve-spring lifting tool comprising a frame, a pair of jaws mounted on said frame, a sleeve, a pair of parallel movement levers pivotally connected at their respective end portions to said frame and to said sleeve respectively, a handle pivotally mounted in the upper portion of said frame adjacent to one of said arms, said handle being provided with a cam having a long straight lower edge face substantially parallel with the opposed edge face of said adjacent arm when in engagement therewith, a thrust link, and pivot pins respectively pivotally connecting the respective end portions of said link to said cam and the distant arm, said lower face of said cam engaging the opposed upper face of the adjacent arm in the closed position of the tool, and in such position the line of thrust of said thrust link extending below and to the rear of the pivotal point of mounting of said handle in said frame, in combination with a post slidably mounted in said sleeve and formed with a vertically extending series of rack teeth, a pinion journaled in said sleeve and meshing with the teeth of said post, means for at will rotating said pinion, a catch straddling the lower rear portion of said sleeve and pivotally mounted on said sleeve for swinging movement toward and from said post, said catch normally operatively engaging the lower face of said sleeve and the opposed upper face of one of the teeth of said series to lock said post against movement in said sleeve away from said jaws under the thrust of the valve-spring being operated upon, and yielding means for normally holding said catch in operative position, said yielding means being adapted to automatically yield under the downward and rearward thrust of the next adjacent upper tooth to permit said post to be moved downward through said sleeve by the rotation of said pinion in the proper direction.

3. A valve-spring lifting tool comprising a frame, a pair of jaws mounted on said frame, a sleeve, a pair of parallel movement levers pivotally connected at their respective end portions to said frame and to said sleeve respectively, a handle pivotally mounted in the upper portion of said frame adjacent to one of said arms, said handle

being provided with a cam having a long straight lower edge face substantially parallel with the opposed edge face of said adjacent arm when in engagement therewith, 5 a thrust link, and pivot pins respectively pivotally connecting the respective end portions of said link to said cam and the distant arm, said lower face of said cam engaging the opposed upper face of the adjacent arm in the closed position of the tool, and in such position the line of thrust of said thrust link extending below and to the rear of the pivotal point of mounting of said handle in said frame, in combination 10 with a post slidably mounted in said sleeve and formed with a vertically extending series of rack teeth, a pinion journaled in said sleeve and meshing with the teeth of said post, and means for at will rotating said 15 pinion.

4. A valve-spring lifting tool comprising a frame, a pair of jaws mounted on said frame, a sleeve, movable connections between said frame and sleeve, a handle pivotally mounted on said frame and means associated with said handle for causing relative movement between said frame and movable connections and in the closed position of the tool exerting thrust on said handle 20 in a line extending below and to the rear of the pivotal point of mounting thereof, in combination with a post slidably mounted in said sleeve and formed with a vertically extending series of rack teeth and having a portion having an unbroken surface extending upward from adjacent to the upper end of said series and lying in line and substantially flush with the tips of the teeth of said series, a presser foot permanently mounted 25 on the lower end of said post and being of greater dimensions in a horizontal direction than the interior of said sleeve, a pinion journaled in said sleeve and meshing with the teeth of said post and having a laterally disposed shaft turning therewith, said pinion in cooperation with said unbroken surface of said post serving to prevent endwise separation of said post from said sleeve in the reverse direction, a control- 30 ling and operating hand grip secured to said shaft, a catch straddling the lower rear portion of said sleeve and pivotally mounted on said sleeve for swinging movement toward and from said post, said catch normally operatively engaging the lower face of said sleeve and the opposed upper face of one of the teeth of said series to lock said post against movement in said sleeve away from said jaws under the thrust of the valve 35 spring being operated upon, and yielding means for normally holding said catch in operative position, said yielding means being adapted to automatically yield under the downward and rearward thrust of the next adjacent upper tooth to permit said post 40 to be moved downward through said sleeve by the rotation of said pinion in the proper direction.

5. A valve-spring lifting tool comprising a frame, a pair of jaws mounted on said frame, a sleeve, movable connections between said frame and sleeve, a handle pivotally mounted on said frame and means associated with said handle for causing relative movement between said frame and movable connections and in the closed position of the tool exerting thrust on said handle in a line extending below and to the rear of the pivotal point of mounting thereof, in combination with a post slidably mounted in said sleeve and formed with a vertically extending series of rack teeth, a pinion journaled in said sleeve and meshing with the teeth of said post, means for at will rotating said pinion, a catch straddling the lower rear portion of said sleeve and pivotally mounted on said sleeve for swinging movement toward and from said post, said catch normally operatively engaging the lower face of said sleeve and the opposed upper face of one of the teeth of said series to lock said post against movement in said sleeve away from said jaws under the thrust of the valve 45 spring being operated upon, and yielding means for normally holding said catch in operative position, said yielding means being adapted to automatically yield under the downward and rearward thrust of the next adjacent upper tooth to permit said post to be moved downward through said sleeve by the rotation of said pinion in the proper direction.

6. A valve-spring lifting tool comprising a frame, a pair of jaws mounted on said frame, a sleeve, movable connections between said frame and sleeve, a handle pivotally mounted on said frame and means associated with said handle for causing relative movement between said frame and movable connections and in the closed position of the tool exerting thrust on said handle in a line extending below and to the rear of the pivotal point of mounting thereof, in combination with a post slidably mounted in said sleeve and having a vertically extending series of rack teeth, a pinion journaled in said sleeve and meshing with the teeth of said post, means for at will rotating said pinion, and means for preventing endwise movement of said post.

In testimony whereof we have signed our names to this specification at Lancaster, Pennsylvania, this 31st day of July, 1931.

HARRY W. KULP.

MARTIN C. DELLINGER.

to be moved downward through said sleeve by the rotation of said pinion in the proper direction.

5. A valve-spring lifting tool comprising a frame, a pair of jaws mounted on said frame, a sleeve, movable connections between said frame and sleeve, a handle pivotally mounted on said frame and means associated with said handle for causing relative movement between said frame and movable connections and in the closed position of the tool exerting thrust on said handle in a line extending below and to the rear of the pivotal point of mounting thereof, in combination with a post slidably mounted in said sleeve and formed with a vertically extending series of rack teeth, a pinion journaled in said sleeve and meshing with the teeth of said post, means for at will rotating said pinion, a catch straddling the lower rear portion of said sleeve and pivotally mounted on said sleeve for swinging movement toward and from said post, said catch normally operatively engaging the lower face of said sleeve and the opposed upper face of one of the teeth of said series to lock said post against movement in said sleeve away from said jaws under the thrust of the valve spring being operated upon, and yielding means for normally holding said catch in operative position, said yielding means being adapted to automatically yield under the downward and rearward thrust of the next adjacent upper tooth to permit said post to be moved downward through said sleeve by the rotation of said pinion in the proper direction.

6. A valve-spring lifting tool comprising a frame, a pair of jaws mounted on said frame, a sleeve, movable connections between said frame and sleeve, a handle pivotally mounted on said frame and means associated with said handle for causing relative movement between said frame and movable connections and in the closed position of the tool exerting thrust on said handle in a line extending below and to the rear of the pivotal point of mounting thereof, in combination with a post slidably mounted in said sleeve and having a vertically extending series of rack teeth, a pinion journaled in said sleeve and meshing with the teeth of said post, means for at will rotating said pinion, and means for preventing endwise movement of said post.

In testimony whereof we have signed our names to this specification at Lancaster, Pennsylvania, this 31st day of July, 1931.
